UNITED STATES PATENT OFFICE.

JOSEPH M. TOWNSEND, OF WORCESTER, MASSACHUSETTS, ASSIGNOR TO TOWNSEND ENVELOPE MACHINE CO., OF BOSTON, MASSACHUSETTS, A CORPORATION OF MASSACHUSETTS.

ENVELOPE MACHINE.

Application filed June 25, 1925. Serial No. 39,472.

This invention relates to envelope machines and with regard to certain more specific features thereof to automatic machines in which a blank or web is treated and formed with folds and if desired supplied with inserts so that a completed, and in some instances filled, envelope passes out from the machine.

In accordance with the rules of practice 10 reference is made to my co-pending application for improvements in envelope making machines, Ser. No. 713,635 filed May 15, 1924.

Reference is also made to my U. S. Letters 15 Patent No. 1,426,523 dated August 22, 1922.

It is one of the objects of the present invention to increase the capacity of such machines and render the extraction of the finished envelopes more certain by an improved 20 ejector device and by the employment of various other improvements which will be specifically referred to hereinafter.

Another object of the invention resides in the addition, to a machine of this general 25 character, of means for assembling an insert with the envelope blank so that a finished and filled envelope issues from the machine.

Other objects lie in the provision of improvements in the mechanism shown in my 30 co-pending application hereinbefore referred to which result in highly effective registration of the blanks at the folding station, extraordinary regularity in seams, continuity of effective operation, turning out 35 envelopes of far-fold type and, uniform gumming of the blanks without causing interruption to the continuous operation of the machine by reason of the blanks adhering to the glue roller, or by reason of the glue or 40 gum distributing to other parts of the machine.

Other objects will be in part obvious and in part pointed out particularly hereinafter.

The machine accordingly consists in the 45 various features of construction, combinations of elements and arrangements of parts which will be exemplified by the construction hereinafter set forth and the scope of the application of which will be indicated 50 in the appended claims.

In the accompanying drawings wherein is

represented one of various possible embodiments of the invention.

Figure 1 is a sectional view taken on a median lengthwise of the machine and showing the forward end thereof with gumming, 55 folding and ejecting devices therefor.

Figure 2 is a sectional view on a slightly reduced scale taken on a median lengthwise of the machine showing the selecting mechanism and some of the feeding and gumming devices.

Figure 3 is a plan view of the forward end of the machine.

Figure 4 is a sectional view taken substantially along the line 4—4 of Figure 3.

Figure 5 is a detailed view of the operating mechanism for the selector.

Figure 5^a is a plan view of the selector disks and operating mechanism.

Figure 6 is a view in perspective of one form of inserting device.

Figure 7 is a view in perspective of another form of inserting device.

Figure 8 is a view showing the actuating 75 mechanism for either of the inserting devices shown in Figures 6 and 7.

Figure 9 is a view in side elevation of a portion of the machine including the gumming mechanism and controlling devices 80 therefor.

Figures 10 and 11 are views of a portion of the controlling devices for the gumming mechanism.

Figure 12 is a view in perspective of the 85 actuating mechanism for the front registers.

Figure 13 is a view in perspective of the actuating mechanism for the ejector.

Figure 14 is a view in perspective of the gum roller showing the stripper plate.

The general operation of the machine which is shown herein as a preferred embodiment is as follows:

A stack or bank of envelope blanks is disposed in a suitable container at the rear of 95 the machine. The foremost blank of the stack is selected and drawn from the stack to present it to the action of the rotary feeding devices which carry it preferably in a substantially straight-line horizontal direction 100 through the machine under certain gumming devices which operate to apply an adhesive.

The blank is then further fed to registration devices which move into and out of position at proper times to locate the blank at a folding station. At the folding station certain blank holding means and a blank folding means are provided and the present invention contemplates also the arrangement of a mechanism for assembling inserts with the blank to be folded. This mechanism is operated in timed relation with the folding and feeding means and is designed to select an insert from a suitable container or stack and supply the same to the blank in position for enclosure by the turning over of the blank flaps under the action of the folding mechanism. There is also a presser which cooperates with the blank holder to set the seams of the folded blank. The present invention involves an additional or auxiliary presser device which in action 15 slightly precedes the movement of the main presser and holds the folded flaps securely in position awaiting the gum setting action of the main presser. After the inserting, folding and pressing operations have been completed an extraction means comes into operation properly positioned and timed to act upon the folded and filled blank to carry it away from the folding station.

Referring now more particularly to the drawings wherein similar reference characters refer to similar parts throughout the different views, the frame of the machine comprises a horizontal table 10 and suitable uprights 11 having journal bearings 12 for a main driving shaft 13. In the embodiment shown all of the operating devices except the suction pump are supported on or by this frame.

The main driving shaft 13 has fixed thereon a plurality of cams for actuating the various mechanisms which treat the blanks as they pass from a stack at the rear of the machine forwardly, until the action of the ejector carries the finished product from the machine. These cams which are shown in Fig. 1 of the drawings are designated as follows:—

A cam A for operating the presser mechanism, a cam B for operating a portion of the folding mechanism, a cam C for operating another portion of the folding mechanism, a cam D for operating the holding block, a cam E for operating another portion of the folding mechanism, and a cam F which controls the action of a distributor in the air line to the suction holding block, timing this distributor to open the line when a blank has been registered over the suction block. The main driving shaft carries a bevelled gear 15 which meshes with a bevelled pinion 16 at the lower end of a shaft 17 which shaft at its upper end is connected through bevelled gearing to a shaft 18 of a selector mechanism. By chain and sprocket connection 19 the selector shaft 18 is connected to the shaft 20 of a gum roller

21. There is also a connection by chain and sprocket mechanism 22 from the selector shaft to a feed shaft 23. This feed shaft is geared as indicated at 24 to another feed shaft 25 directly below the first, and from the lower feed shaft there are a series of chain and sprocket connections to other feed shafts suitably spaced toward the forward end of the machine. The foremost lower feed shaft 26 is by a gear connection indicated at 27 in Fig. 2 of the drawings, connected to a cooperating feed roll shaft 28 directly above.

From the rearward feed shaft 25, there is also a connection by means of a chain and sprocket to the primary shaft of a gum supply mechanism. By a suitable gearing, this primary shaft is connected through an intermediate roller to a pivotally movable gum applying roller. This is a well known type of gum supply mechanism and therefore, it is not shown in the drawings. The gum applying roller is adapted to contact with certain raised areas 30 of gumming roller 21 to coat it with the adhesive which in turn is transmitted by them to the proper areas on the blanks as the latter are successively fed through the machine under the action of the aforesaid feed rollers.

The main driving shaft is connected through suitable clutch means to a main driving pulley (not shown) and the distributor of a suction device is connected to a pump by suitable means (not shown). The distributor head is connected by flexible conduits 31 to a chamber 32 in the suction holding block and by means of the cam F a valve of the distributor is intermittently operated to apply the influence of the suction to the surface of the block. In Figures 6, 7 and 8 of the drawings are shown the inserting mechanism and the actuating means therefor. These comprise a suction device 33 as shown in Fig. 6 or a magnetic carrier 34 as shown in Fig. 7, with rack and pinion means 35 controlled by a cam 36 on the gum roll shaft 20. The suction device 33 and the magnetic carrier 34 are designed for alternative use in the machine according to the character of the insert which it is desired to enclose in the blank. This insert mechanism is arranged between the gum roller and the folding means and operates in timed relation with both of these mechanisms to select an insert from a stack or bank, and deposit it on the blank being folded.

Supported at one end of the horizontal table 10 is a holder 40 for a stack or bank of envelope blanks, a follower 41 is employed to hold the blanks in a compact stack with the front face of the foremost blank registering against a wall 42. The blanks are supported on edge by spaced plates 43 with the extended portions which go to make up the front flap of the envelope projecting downwardly between the plates. A pivotally movable suction tube

44 is arranged slightly in advance of the stacking devices, and this tube is timed for intermittent pivotal movement to bring a pair of apertures 45 at the lower end of the 5 tube over against the front surface of the foremost blank of the stack. This intermittent pivotal movement is accomplished by a cam 46 on the so-called selector shaft, operating on a roller 47 at the end of a short arm 10 48 secured to one of the pivot pins 49 of a frame piece 50, journaled in uprights at either side of the table 10. The frame 50 is in part hollow and is connected by a conduit 51 which extends to the main suction conduit. 15 By the action of the mechanism just described, the foremost blank of the stack is selected and drawn forwardly from the remaining blanks of the stack. This brings the lower end of the selected blank against the 20 peripheries of the three rotating disks 52 of the selector mechanism. The intermediate one of the three disks 52 is provided with a cut-away portion 53 and a pivoted claw 54 which is timed to move so that it will grip 25 the blank by reason of engagement with the rear surface of the blank which has been pulled over so that its front surface engages the edges of the disks 52. The disks on either side of the one with the claw 54 serve as 30 guides or supports for the selected blank after it is withdrawn from the stack. The operating mechanism for the pivoted claw is shown in detail in Figs. 5 and 5^a of the drawings, and consists of a cam 55 actuating a 35 roller 56. The cam 55 is fixed to the frame of the machine and causes the roller 56 to be moved around a shaft 57 which is in the form of a pin projecting from a disk 58 fixed on the shaft 18. This is by reason of the fact that 40 the roller 56 is on the end of a short lever 59 which is mounted on the pin 57. The lever 59 is provided with an extension beyond the roller 56 which is formed with the segmental gear 60 taken on a radius from the center of 45 pin 57. The segmental gear 60 meshes with a pinion 61 fixed on a shaft 62 which carries the claw 54. The lever 59 is provided with another extension 63 beyond the pivot point 57 and between this extension and a fixed post 50 64 extending from the disk 58, there is a spring 65 tending to return the roller 56 to the low points of the cam 55. This mechanism is timed to rotate the claw 18 into gripping relation with the periphery of the middle disk 52 just after the suction-device has 55 withdrawn the lower end of the foremost blank from the stack, so that from the suction device the blank will be carried by the claw 54 first in a downward direction and then 60 forwardly to introduce the blank to the feeding mechanism.

From the selector the blank is passed over idler rollers 70 between the upper and lower guides 71 and 72 respectively to positively driven rollers 73 and 74. From these feed

rollers the blank is passed forwardly to another pair of feed rollers 75 and 76, the lower roller 76 being positively driven by chain and sprocket connection 77, and the upper roller 75 bearing against the lower roll under the 70 influence of gravity and pressure applied by suitable spring means fixed to the frame of the machine.

The gum roller 21 mounted on shaft 20 is supported by the journaling of its shaft in 75 suitable upright brackets 80 at either side of the table 10. Directly below the gumming roller is a cooperating roller 81 loosely mounted on a shaft 82 which in turn is journaled in short rocker arms 83 extending from a shaft 80 84 suitably journaled in uprights on either side of the machine. A spring 85 is interposed between the table 10 and shaft 82 tending to hold the latter upwardly against an adjustable box 86 fixed to the frame of the 85 machine. This box 86 is adjusted to permit the roller 81 to cooperate with the gumming roller, but inasmuch as it is desirable to interrupt this cooperative relationship at times, a cam control mechanism has been introduced 90 to the machine, and this mechanism is primarily controlled by the feed of the blanks through the machine. Referring to Figure 9 of the drawings, it will be noted that a lever 90, pivoted on a shaft 91, is arranged in the 95 path of feed of the blanks. Fixed to the shaft 91 is a rocker arm 92 having pivotal connection with a connecting rod 93 which in turn connects with the lower end of a lever 94 pivoted at 95 on the frame of the machine. 100 The upper end of lever 94 has a pivotal connection with a slide 95 shown more clearly in Figures 10 and 11 of the drawings. This slide 95 has a slot 96 at its free end which under the action of the rod and lever mechanism described moves into and out of registration with a pin 97 depending from a lever 98 pivotally mounted as shown in Figure 9 of the drawings on the shaft 84. This lever carries a cam roll 100 directly above the pin 110 97, and at the opposite end of the lever, there is a spring 101 which tends to hold the cam roller 100 in engagement with a cam 102 on the gum roller shaft 20. When blanks are passing through the machine they act upon 115 the lever 90 to rock the shaft 91 and throw the slide 95 into position of registration of its slot 96 with the pin 97 on lever 98, there is an idle action of the cam 102 on the roller 100. This results in idle movements of the 120 lever 98 about the shaft 84 without having any effect upon the roller 81. Under these conditions the roller 81 is held in cooperative relationship with the gum roller 21 by means of the spring 85. In order that the gum on 125 the roller 21 shall not be transmitted to the roller 81 the cam 102 operates to throw the roller 81 periodically downward, as the gummed areas of the roller 21 pass by, provided, of course, no blanks are coming 130

through the machine. This is accomplished by the slide 95 assuming a position by reason of the weight of the lever 90, in which the slot 66 is out of registration with the pin 97, so that whatever action is given to the lever 98 by reason of the cam 102 is transmitted to the roller 81.

From the gumming station a blank with its flaps properly gummed is passed on to the folding station. (See Figures 1, 3 and 4 of the drawings.) The feed rollers 110 and 111 fixed respectively on shafts 28 and 26 pass the blank between upper and lower guides 112 and 113 onto a suction holding block 115. This block which may take any desired form is shown in the present embodiment as rectangular and arranged for cooperation with four folding fingers which may be designated as rear folding finger 120, front folding finger 121, and side folding fingers 122. This block and the actuating means therefor are substantially the same as shown in my co-pending application above referred to, and therefore, will not be described in detail further than to state that the block has a short up and down movement under the influence of actuating cam D and the folding fingers are timed in relation to the movement of the block to move inwardly to fold the flaps of the blank in proper sequence as the holding block moves to its lowermost position. The front folder 121 is designed to give the crease at the top of the envelope, and this flap which has been gummed is not folded into contact with the remainder of the envelope blank. During the folding operation a pair of ejector fingers 130 are rocked on a shaft 131 into position where the take-off clips 132 locate behind the cover flap of the folded blank. As the block 115 moves upwardly, the ejector fingers 130 rock forwardly with comparative quick action by means of a cam 133 shown in Figure 13 of the drawings. This cam operates on a roller 134 at the forward end of a spring held yoke 135, and this yoke is connected to the rock shaft 131 by a rod 136 and a rocker arm 137.

New and improved means have been devised for effecting the front registration of the blanks opposite the suction holding table. Figure 3 of the drawings shows these forward registers at 140 as upstanding cylindrical posts and adjustably connected as indicated at 141 to slides 142 arranged in ways 55 143 fixed to the table at either side. These slides are connected by a rod 144 and levers 145 and 146, so that they move inwardly or outwardly in unison. A cam 147 on the gum roller shaft contacts with a cam roller 148 at the upper end of a lever 149 pivoted to the frame at 150, and the lower end of this lever 149 is connected by a rod 151 to the lever 146. This operates the front register slides out of registered position to permit the folded blank to be ejected from the machine.

Spring means 152 effect the inward movement of the slides as the high portion of the cam 147 passes its cam roller.

To set the gummed flaps of the folded blanks a presser device is provided which in many respects corresponds to the one shown in my co-pending application above referred to. In the present instance, however, an additional holding and pressing mechanism is attached to the main presser pad 160. This comprises two advance fingers 170 normally held somewhat below the presser surface 171 of the pad 160 by springs 172 reacting upon arms 173 which are fixed on the main pad 160. The downward throw of the fingers 170 is limited by adjustable collars 174. Near the end of the folding operation the presser is moved downwardly. Under the action of the cam A the advance fingers are moved into yielding contact with the inturned side flaps of the blank holding them securely in position while the main presser pad follows into contact with the folded rear flap. The action of the latter pad sets the gum along the back seams 90 of the envelope and then the presser mechanism moves upwardly followed by the holding block.

Referring now to the mechanism for stripping the blanks from the gummed roller (see Figures 1, 2, 3 and 14) a stripper plate 180 arranged on the gum roller 21 is normally held by a spring 181 with its surface below or within the gumming surface 182 of the roller. This stripper plate is connected to a wiper 183 which is pivotally mounted on the gum roller as indicated in Figure 14 at 184. A cam 185 (see Figure 2) fixed on the gum roller shaft 20 operates a cam roll carrying rocker arm 186 fixed on a rock shaft 187 journaled in suitable bearings in an upright 188 fixed to the main frame of the machine. This rock shaft has disposed at one end another cam roll carrying rocker-arm 189 in the plane of the stripper plate wiper 183. By this means a roller 190 is thrown periodically into the path of the wiper 183 so that the stripper plate 180 will be moved outwardly beyond the gumming surface of the gum roller. The stripper plate is mounted on the gum roller adjacent the advance gumming pad 182 so that the machine in its operation with the gum roller turning in the direction of the arrow indicated in Figure 1 first gums the forward flap of a blank, whereupon the stripper plate comes immediately into action to prevent the blank from following the rotary path of the gum roller. This stripper action directs the forward end of the blank between the upper and lower guides 112 and 113, so that the blank may be picked up by the feed rollers 110 and 111 and passed on to the devices for registering, holding and folding the blank.

Preferably the suction holding block 115 is 130

of the general type shown in my United States Letters Patent No. 1,426,523 dated August 22, 1922, and involves a series of suction apertures located near the outer edge 5 so as to securely hold the blank near the line of fold. The arrangement of the block with the folding fingers so that relative movement causes a preliminary turning-in action of the blank flaps has been found to be advantageous to the operation of this machine. It is to be noted, however, that the present invention in many aspects is not limited to the use of a suction block or to the employment of the previously mentioned relative movement 10 between the block and the folding fingers.

As many changes could be made in the above construction and as many apparently widely different embodiments of the invention 15 might be made without departing from the scope thereof, it is intended that all matter shown in the accompanying drawings or set forth in this description shall be interpreted as illustrative and not in a limiting 20 sense.

Claims:—

1. In a machine of the character described, in combination, work feeding means, work folding means and an ejector for the finished 25 work, said ejector comprising a device, operating in timed relation with the feeding means, adapted to rock into position behind a portion of the work and by a reverse rocking motion catch into a fold in the work and carry it from the machine in a line with the feed of said work to the folding means.

2. In a machine of the character described, in combination, blank feeding means, a folder comprising a holding block for the blank and 30 folding fingers relatively movable with said block, an ejector device comprising a member which moves over the forward edge of the blank during the folding operation and takes a position behind one of the folds as the holding block completes its relative movement 35 with the folding fingers, and means for throwing the ejector member forwardly to extract the blank.

3. In a machine of the character described, 40 in combination, work feeding means, a folder for the work comprising a suction holding device and folding fingers, means for actuating the suction holding device toward and away from the line of feed, an extraction finger, and means for moving said extraction finger over the forward edge of the folded work while the holding device is away from the line of feed, and having provision for causing the finger to take in to the work behind a fold and eject the work as the holder 45 returns toward the line of feed.

4. In a machine of the character described, 50 in combination, work feeding means, a movable member for applying adhesive to the work, stripping means carried by said mov-

able member and operating in timed relation with the feeding means for insuring detachment of the work from the adhesive applying member.

5. In a machine of the character described, 55 in combination, work feeding means, a movable member for applying adhesive to the work, stripping means comprising a pivoted element arranged at the surface of the adhesive applying member, and an actuator 60 therefor having provision for moving a portion of the pivoted element intermittently beyond the surface of said adhesive applying member.

6. In a machine of the character described, 65 in combination, a gumming roller having surface portions adapted to receive and transmit gum, means for rotating said gumming roller, a stripper pivoted in said roller and normally held from projection beyond the 70 gumming surface portions, and means adapted to act intermittently on said stripper to cause a portion thereof to project beyond the gumming surface.

7. In a machine of the character described, 75 in combination, a selecting and feeding mechanism for envelope blanks, means for gumming the flaps of said blanks comprising a gum roller having surface portions adapted to receive and transmit the gum, a stripping 80 mechanism comprising a member arranged within the gum roller normally at or below the said surface portions and means operative in timed relation with the selecting, feeding and gumming means adapted to periodically 85 actuate the stripper member.

8. In a machine of the character described, 90 in combination, a blank gumming device comprising a pair of intermittently cooperative rollers one of which has surface forms for receiving and transmitting the gum, a gum 95 supply roller, a stripper mounted on the receiving and transmitting roller and actuating means therefor comprising a member periodically moved into the rotary path of the 100 stripper.

9. In a machine of the character described, 105 in combination, rotary means for selecting and feeding blanks, a rotary gumming element in the line of feed, a rotary element arranged for cooperation with the gumming element, and means comprising a lever arranged in the line of feed and adapted to be 110 acted upon by the blanks being fed, whereby a cooperative relationship is established between said gumming element and the said cooperative rotary element, the latter said means having provision for discontinuing 115 said relationship when no blanks are being fed.

10. In a machine of the character described, 120 in combination, a device for selecting blanks from a stack, a feeding mechanism whereby successive blanks are given a line feed, a gumming mechanism comprising two 125

- rollers adapted for intermittent cooperation, means for supplying an adhesive to one of the rollers for transmission to the blanks, cam means for regulating the action of one roller 5 toward and from the other, and a finger arranged in the path of feed and connected with a control device whereby said cam means are rendered ineffectual during the feed of the blanks.
- 10 11. In a machine of the character described, in combination, work feeding means, an adhesive applying member, a folding device whereby certain gummed portions of the work are laid over other portions thereof, a 15 presser adapted to bear upon the work adjacent the gummed portions and auxiliary presser means preceding the first said presser in contact with the work whereby certain folds are firmly held in preparation for the 20 action of the first said presser.

12. In an envelope folding machine, a de-

vice for gumming certain portions of an envelope blank, a folder for the gummed blank, presser means for operation on the blank at the end of the folding operation, said means comprising a main presser which bears upon the gummed laps and an auxiliary presser comprising spring held yieldable fingers arranged to come to bear upon the side flaps of the envelope in advance of the contact of the 25 main presser.

13. In a machine of the character described, in combination, blank feeding means, blank folding mechanism, a forward register for the blanks fed to the folding mechanism, said 30 register comprising oppositely disposed slides having upstanding register fingers, said slides being controlled by cam means to move the fingers into and out of register position.

JOSEPH M. TOWNSEND.
